UNITED STATES PATENT OFFICE.

JAMES B. LAWTON, OF CINCINNATI, OHIO.

ROLL-PAPER HOLDER AND CUTTER.

SPECIFICATION forming part of Letters Patent No. 428,565, dated March 18, 1890.

Application filed September 26, 1888. Serial No. 286,425. (No model.)

To all whom it may concern:

Be it known that I, JAMES B. LAWTON, a citizen of the United States, residing at Cincinnati, in the county of Hamilton and State 5 of Ohio, have invented certain new and useful Improvements in Roll-Paper Holders and Cutters, of which the following is a full, clear, and exact description, reference being had to the accompanying drawings, forming part of 10 this specification.

My invention relates to that class of wrapping-paper holders now in general use in stores, in which the paper is in a continuous roll and is drawn and cut therefrom in sheets 15 of proper size as required for use; and it has for its object the improvement in the construction of this class of devices.

The novelty of my invention will be here- 20 with set forth, and specifically pointed out in the claims.

In the accompanying drawings, Figure 1 is a front elevation of a roll-paper holder embodying my invention. Fig. 2 is an end elevation of the same. Fig. 3 is an end elevation 25 of the same with modifications. Figs. 4, 5, 6, 7, 8, 9, and 10 are enlarged details to be referred to more particularly hereinafter.

The same letters of reference are used to indicate identical parts in all the figures.

30 A is the usual bed-plate, upon which are secured the two uprights B, braced by the top piece C, in the usual or any suitable manner. The uprights B have recessed lugs a (see Fig. 6) upon their inner sides, in which the 35 ends of the spindle D, carrying the paper-roll E, rest, thereby enabling the roll to be inserted from either side, which, in the case of heavy rolls, and owing to the sometimes fixed position of the holder, is a great convenience. 40 The spindle D is passed through the usual centering-plugs F, inserted in the roll in the customary manner.

The knife-bar G can be made quite light, and it is carried upon the upper ends of two 45 supporting guide-rods H, whose lower ends are inserted in vertically-inclined apertures b, Figs. 7 and 8, extending through the uprights B. Under one and the preferred form of construction (see Fig. 10) the upper end of 50 each guide-rod H is threaded and inserted through a slightly enlarged or countersunk aperture c in the end of the knife and has a

ball-weight I, made in any ornamental shape desired, screwed upon it. The knife is thus confined at each end between the ball I and 55 a swell or collar d upon the rod H, but with sufficient play to enable the knife to rise and fall at either end to follow any inequalities in the roll, as will be readily understood. The balls I serve to hold the knife snugly to 60 the surface of the roll, and, if desired, other balls may be secured to the lower projecting ends of the rods H, as where very tough or heavy paper is employed; or, instead of or in connection with the upper balls, springs J, 65 Fig. 3, may be secured at their lower ends to the bed A and have their upper ends removably connected to the lower ends of the rods H.

As a means for holding the knife to the paper and preventing its being lifted during 70 the act of cutting off the paper each rod H has serrations or notches upon its under lower side, and the aperture b is vertically enlarged at its lower end, (see Fig. 7,) and an engaging-plate e, secured to or formed integral with 75 the upright B, projects slightly above the lower edge of the aperture b in such manner that when the projecting end of the paper is lifted to cut it off the rods H will be tilted and their lower serrated ends will be caught 80 and engaged by the plates e, thereby locking the knife, as will be readily understood. As soon as the paper has been severed the weight of the parts retails the rods H and disengages them from the plates e, in which position the 85 rods H are free to move up and down to permit the knife G to follow any inequalities of the roll and to descend as the roll gradually decreases in diameter. Of course the location of the devices just described could be 90 reversed, as seen in Fig. 8, to accomplish the same result. Where light paper is used there will be no necessity for the plates e and the serrations in the rods H, nor need the rods H have any other than longitudinal play in the 95 apertures b.

As a means for rotating the roll E to bring the severed edge out from under the knife, I construct one of the plugs F (see Figs. 4 and 5) of metal, with a ratchet f formed near its outer end and with a peripheral groove g. Loosely encompassing the outer end of this plug is an arm or handle K, (see Figs. 1, 2, 3, and 5,) provided with a spring-dog h, which

engages with the ratchet *f* upon the plug, and which arm is held from lateral displacement by one or more set-screws *i* in the handle and entering the groove *g*. It will be seen from 5 this construction that by pressing down the handle the engagement of the dog *h* with the ratchet *f* turns the roll forward, while the return or lifting of the handle permits the dog to slip back over the ratchet without returning the roll. If desired, a spring *L* may be employed to hold the handle up and to return it after it is depressed. As seen in Fig. 1, the handle is bent out to clear the end of the knife.

Instead of the dog and ratchet any known 15 form of clutch mechanism may be employed, and in Fig. 9 I have shown one of such forms, where a ball *j* is confined in a cam-recess *k* in the bore of the handle and engages when the handle is pressed down with the periphery of 20 the plug, as will be readily understood.

Having thus fully described my invention, I claim—

1. In a paper-roll holder, the combination of the paper-roll and its supports provided 25 with the vertically-inclined guides made larger at one end than at the other, the rods inserted through and free to move in said guides and having serrated lower portions, the catches arranged to engage with the serrations on said rods when the latter are tilted 30 by the severing of the paper from the roll, and the cutter-blade carried on the upper ends of said rods and resting on the surface of the paper-roll, substantially as and for the purpose described.

2. In a paper-roll holder, the combination, with the paper-roll, the cutter-blade, and supports for said roll and blade, of a handle pivoted substantially concentric with the axis 40 of the paper-roll and connected thereto and arranged to turn the same when moved in one direction, but free to be moved in the opposite direction without turning the roll, substantially as and for the purpose described.

3. In a paper-roll holder, the combination, with the paper-roll, the cutter-blade, and supports for said roll and blade, of a handle pivoted substantially concentric with the axis 45 of the paper-roll and connected thereto by ratchet-and-pawl devices and arranged to turn the same when moved in one direction, but free to be moved in the opposite direction without turning the roll, substantially as and for the purpose described.

4. In a paper-roll holder, the combination of the paper-roll and its supports provided with the vertically-inclined guides, the rods inserted through and free to move in said guides, the cutter-blades secured to the upper ends of said rods and resting on the surface of the paper-roll, and the handle connected to said roll and arranged to turn the same when moved in one direction, but free

to be moved in the opposite direction without turning the roll, substantially as and for the purpose described. 65

5. The combination of the paper-roll *E*, supports *B*, vertically-inclined guides *b*, rods *H*, passed through said guides and provided with the collars *d* near their upper ends, the weights *I*, secured on the upper ends of the rods *H*, and the cutter-blade *G*, carried on the upper ends of said rods and loosely confined between the weights *I* and collars *d* and resting on the surface of the roll *E*, substantially 75 as and for the purpose described.

6. The combination of the paper-roll *E*, supports *B*, vertically-inclined guides *b*, rods *H*, passed through said guides and provided with the lower serrated portions, the catches 80 *e*, normally free from but arranged to engage said serrated portions when the rods *H* are tilted in their guides by the severing of the paper, and the cutter-blade *G*, carried by the rods *H* and resting on the surface of the paper-roll, substantially as and for the purpose described. 85

7. The combination of the paper-roll *E*, supports *B*, vertically-inclined guides *b*, rods *H*, passed through said guides and provided with the lower serrated portions, the catches 90 *e*, normally free from but arranged to engage said serrated portions when the rods *H* are tilted in their guides by the severing of the paper, and the weights *I* and cutter-blade *G*, 95 carried by the rods *H*, substantially as and for the purpose described.

8. The combination, with the paper-roll, the cutter-blade, and supports for said roll and blade, of the handle *K*, connected to the paper-roll by ratchet-and-pawl devices and arranged to move the roll with it when turned in a forward direction and to move in the opposite direction without turning the roll, substantially as and for the purpose described. 100

9. The combination, with the paper-roll, the cutter-blade, and supports for said roll and blade, of the handle *K*, connected to the paper-roll by ratchet-and-pawl devices, and the resetting-spring *L*, substantially as and for the purpose described. 105

10. The combination of the paper-roll *E*, supports *B*, provided with guides *b*, rods *H*, passed through said guides and provided near their upper ends with the collars *d*, the cutter-blade *G*, provided with the apertures *c*, fitting loosely on the upper ends of the rods *H*, above the collars *d*, and nuts or equivalent devices on the upper ends of the rods *H* for holding the cutter-blade *G* thereon, substantially 115 as and for the purpose described.
